UNITED STATES PATENT OFFICE.

WILLIAM H. STEDMAN, OF HARTFORD, CONNECTICUT, ASSIGNOR TO THE MERROW MACHINE COMPANY, OF HARTFORD, CONNECTICUT, A CORPORATION OF CONNECTICUT.

RACEWAY FOR STITCH-FORMING RECIPROCATING ELEMENTS.

1,086,790.

Specification of Letters Patent.

Patented Feb. 10, 1914.

Application filed December 23, 1910. Serial No. 598,972.

To all whom it may concern:

Be it known that I, WILLIAM H. STEDMAN, a citizen of the United States, residing in Hartford, county of Hartford, State 5 of Connecticut, have invented certain new and useful Improvements in Raceways for Stitch - Forming Reciprocating Elements; and I do hereby declare the following to be a full, clear, and exact description of the 10 same, reference being had to the accompanying drawings, forming a part of this specification, and to the characters of reference marked on the said drawings.

The object of this invention is to provide 15 a raceway capable of a great amount of use with very little resulting wear, also one, the several parts of which are easily constructed and readily assembled.

The invention consists in a device having 20 the qualities mentioned and as set forth and claimed hereinafter.

The invention aims particularly to improve the door or so-called frame cap of 25 crocheting and overseaming machines of the well known Merrow type and an embodiment of the invention is shown and described in connection with such type of machine. The function and general construction of the frame cap will be readily understood by reference to Patent #441,315 issued November 25, 1890 to Joseph M. Merrow for improvements in "crochet machines," the said function in brief being to support certain operating parts of the 30 machine mechanism and to close an opening in the machine frame through which interior mechanism of the machine is accessible. In the present instance, however, the frame cap is shown and described as applied to an 35 overseam sewing machine, the same in general character as that for which Letters Patent #591,049 were issued October 5th, 1897 to Joseph M. Merrow.

In the drawings:—Figure 1 shows in dotted lines the partial outline of an overseaming machine and the frame cap and shows in full lines the reciprocating element or block (here the lower looper carrier) and mechanism for actuating the reciprocating 40 element. Fig. 2 shows in full lines an edge view of the frame cap with the lower looper carrier mounted thereon and in dotted lines adjacent mechanism and portions of the machine. Fig. 3 is an elevation of the inner

face of the frame cap etc., as shown in full 55 lines in Fig. 2 viewed from the left hand of the said figure. Fig. 4 is a view, similar to Fig. 3, showing the reverse or outer face of the frame cap etc. Fig. 5 is an elevation of a portion of the inner face of the frame cap, 60 largely stripped of related elements. Fig. 6 shows an element of the raceway, detached. Fig. 7 is a sectional view, illustrating a portion of the frame cap with the raceway arranged thereon. 65

Like reference characters throughout the several figures denote the same parts.

The number 10 indicates the frame of the machine, 11 the head, 12 the main shaft, 13 the hand and drive wheel, 14 the upper 70 shaft, 12^A—14^A meshing gears on cylindrical cams 12^B—14^B respectively, on the shafts 12 and 14 and having cam grooves 12^C—14^C.

The number 20 denotes the frame cap, 20 the lower looper carrier mounted to reciprocate in a raceway on the frame cap, 18 the upper looper carrier pivotally mounted by its stud 18^A upon the lower looper carrier 20, the latter having a hub 21 in which the said stud has a bearing space. 80

18^B indicates the upper looper carrier cam rolls which engage the cam grooves 12^C—14^C, and 16 and 17 denote respectively the lower and upper loopers. The frame cap is recessed at 30^B to receive the lower looper 85 carrier hub 21 and is provided with an opening 30^C to permit a thread take-up 50 formed on the hub to project through the frame cap.

The very rapid reciprocatory motion of 90 the lower looper carrier is imparted thereto through the upper looper carrier which is actuated with a combined oscillatory and reciprocatory motion by the cylindrical cams, the reciprocatory motion being permitted because of the capability of the lower looper carrier to travel in the raceway on the frame cap. 95

Describing more particularly the frame cap and raceway,—the number 31 denotes 100 the adjustable gib and 32 the fixed gib forming the side walls of the raceway and secured to the frame cap by the screws 33 and 33^A respectively. The number 34 denotes the gib adjusting wedge or key that is 105 located between the gib 31 and the frame cap shoulder 30^A and the number 35 denotes the wedge screw.

As heretofore constructed and as shown in the Patent #441,315 the frame cap has been provided with a locating rib for the gib 32, the gib being channeled to receive the said rib. It has been found advantageous however to discard the rib, to enable the surface 30^D which the gib 32 engages to be readily ground in a plane common also to the surface 30^D engaged by the gib 31 and 10 with a surface on a piece 40 which provides a bottom for the raceway, the said plane extending from the frame cap channel 30^E to the shoulder 30^F. In lieu of the locating rib, the screws 33^A are provided under the 15 head with a cylindrical body portion 33^B which is of slightly greater diameter than the threaded portion of the screw and is adapted to be located partly in the frame cap and partly in the gib and the said body 20 portion is made so close a fit in the holes therefor in the frame cap and gib that the screws serve as dowels and effect the accurate locating of the gib.

To increase the wearing properties of the 25 raceway, the bottom wall is made of a separate piece 40 of steel or other material harder than the frame cap and capable of better withstanding wear. The piece 40 is inlaid, preferably by dovetailing into the frame cap, 30 and may be secured against longitudinal displacement in the dovetail groove by doweling as at 41, Figs. 5 and 6, and the piece 40 has suitable openings registering with the frame cap recess 30^B and the take-up 35 opening 30^C and also with screw holes 43, Fig. 6, for screws to attach a part not shown in the drawings.

When the inlaid piece 40 is in its seat, the 40 wearing face or surface which forms the bottom wall of the raceway is in the plane of the surfaces 30^D engaged by the gibs 31 and 32, or at least the said wearing surface of the inlaid piece and the surfaces 30^D may be readily ground (if necessary) to a common plane after the seating of the inlaid 45 piece, to enable the proper assembling of the gibs 31 and 32 upon the frame cap 30.

The gibs preferably overlap the inlaid piece, the width of the wearing face of the 50 said piece being somewhat greater than the bottom wall of the raceway so that the entire wearing surface for the raceway bottom is provided by the piece of inlaid material, as shown in Fig. 7.

55 The piece 40, if made with sufficient accuracy can easily be renewed.

While the gib 31 is preferably constructed to permit the taking up laterally of wear caused by the reciprocating element 20, the 60 gibs 31 and 32 are secured to their common

support (the frame cap) in relatively stationary or fixed positions, as regards longitudinal movement with reference to each other and to the frame cap.

Having thus described my invention, I claim:

1. In a sewing machine, a raceway for stitch forming reciprocating elements including in combination, two side wall pieces located in a single plane, a bottom wall piece 70 of suitable wear resisting material and a common support for same, one of the said side wall pieces being adjustably secured to the support and the other being held in fixed relation thereto on a plane face of the support and cylindrical elements fitting in and holding in alinement registering bores in the said side wall piece and support, respectively.

2. In a sewing machine in combination 80 with a suitable support, a raceway comprising two removable side wall pieces and a removable bottom wall piece, one of the said side wall pieces being fixedly secured to the support by means including a plurality 85 of screws each having a cylindrical portion formed thereon that accurately fits alined cylindrical passages in the support and side wall piece respectively, for preventing lateral movement of the same, the other side 90 wall piece being adjustably secured to the said support, means for effecting the lateral adjustment of the said wall piece, and means for securing the bottom wall piece to the support. 95

3. In a raceway for stitch forming reciprocating elements, a support having two surfaces finished in a plane common to both and having a dove-tail channel between the surfaces, two side wall pieces secured to the 100 support on the said surfaces respectively and a bottom wall piece mounted in the dove-tail channel the side wall and bottom wall pieces being stationary longitudinally with relation to each other. 105

4. In a raceway for stitch forming reciprocating elements, a support for the raceway, a bottom wall piece inlaid in the support and having a wearing face, said support having surfaces located in the plane of the wearing 110 face of the inlaid piece, and two side wall pieces secured on the said surfaces and overlapping the inlaid piece at its opposite edges the side wall and bottom wall pieces being stationary longitudinally with relation to each other.

WILLIAM H. STEDMAN.
